(57) **CLAIM**

I claim, the ornamental design for a wearable device with image display screen, as shown and described.

DESCRIPTION

FIG. 1 is a front view of a wearable device with image display screen showing new design;

FIG. 2 is a rear view thereof;

FIG. 3 is a right side view thereof;

FIG. 4 is a left side view thereof;

FIG. 5 is a top view thereof;

FIG. 6 is a bottom view thereof; and,

FIG. 7 is a bottom left side perspective view thereof.

The image display device is used in a state in which the image display device is worn or carried on arms, legs, etc.

1 Claim, 4 Drawing Sheets
